UNITED STATES PATENT OFFICE.

HORRY C. BUNNELL, OF WESTPORT, NEW YORK.

RAILROAD-RAIL BRACE.

1,354,239.

Specification of Letters Patent. Patented Sept. 28, 1920.

Application filed May 10, 1920. Serial No. 380,092.

To all whom it may concern:

Be it known that I, HORRY C. BUNNELL, a citizen of the United States, residing at Westport, in the county of Essex and the 5 State of New York, have invented certain new and useful Improvements in Railroad-Rail Braces, of which the following is a specification.

This invention relates to a brace adapted 10 to hold parallel rails in position and to prevent their spreading, or tilting on curves. Many accidents are due to spreading of the rails, and where a road is banked, as at a curve, a slight settling of the banked portion 15 will throw such weight on the rail that it is liable to be tilted, thus derailing the train. My device will not only prevent spreading at all points but by reason of its engagement with the ball or tread portion 20 of the rail, on the outer side, will brace the rail against any tilting movement.

In the accompanying drawings:—

Figure 1 is a side elevation, partly broken away.

25 Fig. 2 is a top plan view of the parts shown in Fig. 1.

In these drawings A designates the base of a rail, B the web and C the ball or tread portion. It is understood that there is a 30 companion rail parallel to the one shown but as the construction is the same on each side of the track only one has been illustrated.

Arranged transversely with respect to the 35 rails and between ties, not shown, are flat bars 1 which pass under the rail bases A, said bars overlapping as shown at their inner end portions.

One of these bars will be described in detail 40 as follows:—The outer end portion of the bar is angled as at 2 to fit snugly the outer edge of the rail base, having an upwardly extending inwardly inclined arm 3

terminating in a beveled edge 4 that engages the point of juncture between the web B 45 and the tread portion of the rail C. This will prevent tipping or tilting action of the rail as long as the bar 1 is in place. On its inner face and adjacent the angled portion 2 the bar has an inwardly extending lug 5 50 adapted to grip the upper face of the outer portion of the base A. A block 6 is arranged on the bar 1 adjacent the inner edge of the base A and has a laterally extending arm 7 engaging the upper face of the base, the block being secured by a bolt 8 and nut 10.

A longitudinally reinforcing plate 11 is fitted on the under face of the bar and is also held in place by the bolt 8 and nut 10. 60 Said bar extends under the block and partly under the rail base.

The overlapping portions of the bars 1 are bolted together as at 12 and a wood or fiber filler 13 is placed between them as at 13 to 65 insulate one rail from the other, fiber bushings 9 being employed for the bolts 12.

The simplicity and advantages of a brace bar of this construction will be apparent.

What I claim is:—

In a brace of the kind described, the combination with a rail, a brace bar passing under the rail base and angled to engage the outer edge of the base, said bar having an arm extending upwardly and inwardly 75 and bearing against the rail at the juncture of the web and tread, a lug formed on the bar engaging the outer face of the base, a block secured to the bar and engaging the inner face of the base, and a longitudinally 80 extending reinforcing plate secured on the under side of the bar and below said block and partly under the rail base.

In testimony whereof I affix my signature.

HORRY C. BUNNELL.
